MOCK HINGE STRAP

Raymond U. H. Tegner, Lodi, Wis., assignor to Amerock Corporation, Rockford, Ill.

Continuation-in-part of abandoned design applications
Ser. No. 209,501 and Ser. No. 209,502, both Dec. 17,
1971. This application Dec. 6, 1972, Ser. No. 312,781

Term of patent 14 years

Int. Cl. D8—07

U.S. Cl. D8—202

FIG. 1.

FIG. 2.

FIG. 3.

FIG. 4.

FIG. 5.

FIG. 1 is a front view of a mock hinge strap incorporating my new design.

FIG. 2 is a side view as seen from the bottom in FIG. 1.

FIG. 3 is an enlarged end view as seen from the left in FIG. 1.

FIG. 4 is an enlarged end view as seen from the right in FIG. 1.

FIG. 5 is an enlarged sectional view taken along the line 5—5 in FIG. 1 with parts broken away for convenience of illustration.

This application is a continuation-in-part of my co-pending applications Ser. No. 209,501, filed Dec. 17, 1971 and Ser. No. 209,502, filed Dec. 17, 1971, both now abandoned.

I claim:

The ornamental design for mock hinge strap, as shown and described.
